UNITED STATES PATENT OFFICE.

ALFRED G. WHEELER, OF DETROIT, MICHIGAN.

GARAGE CONSTRUCTION.

Application filed May 25, 1925. Serial No. 32,765.

This invention relates to building constructions and refers more particularly to a garage building.

One of the objects of the invention is to provide an improved garage designed to eliminate collision hazard between vehicles entering and leaving the building or between such vehicles when stored or operated within the building. A further feature of the invention resides in a garage construction affording a large storage capacity; also the provision of stalls or the like whereby the operators or drivers of the vehicles can readily park their cars or drive them from their parked position without requiring the assistance of garage or other attendants.

A further object is to provide a garage capable of handling a large number of cars or vehicles without relative interference or congestion.

With the above and other objects in view the invention provides for parking cars in such a fashion that the possibility of collision between cars entering or leaving the various parking spaces is avoided. In carrying out these objects I preferably provide a garage having a pair of concentric superimposed spiral passages or drive ways, one spiral adapted to accommodate traffic entering the garage and the other for leaving the same. Means is also provided for crossing over on substantially level cross passages from the entrance spiral to the exit spiral or vice versa, at the points along the axis of the spirals where the entrance and exit spirals would cross each other if the spirals were projected on a vertical plane. A further object of the invention resides in the provision of means for parking cars on both the entrance and exit spirals throughout their length and if desired also at the points of the said cross passages.

With these and other objects in view, the invention resides in the novel features of construction and combination and arrangements of parts as more fully hereinafter described and claimed.

Referring to the drawings in which like reference characters indicate corresponding parts,

Figure 1 represents a perspective view of the garage with the walls thereof broken away to show the arrangement of the concentric spiral passages, and

Figure 2 is a plan view illustrating one

manner of arrangement of the parking stalls for the vehicles.

The construction preferably consists in providing a pair of concentric superimposed spirals indicated at A and B respectively, 60 one of which is adapted to be used for traffic entering the garage, as the spiral B, and the other of which is adapted to be used for traffic leaving the garage as indicated at A. The spiral floors A and B are at all points 65 throughout their length equally vertically spaced apart a sufficient distance to receive a vehicle such as an automobile as shown in Figure 1. The pitch of each of the spirals A and B is preferably twice the distance between adjacent spirals A and B whereby 70 the cars operating on the spirals are respectively sparated from each other during their course of travel.

In the embodiment of my invention as 75 shown in Figure 1, C designates the point of entrance from the street to the garage by way of the spiral B. Tracing the path of a car entering at the point C the car would travel on the spiral B around the axis 80 of the spiral which may coincide with the axial center of the building and when the car reaches the side of the building corresponding to the point of entrance C it will be travelling on the portion 10 of the spiral 85 B. Thus it will be noted that in travelling around the building on the spiral B the car has travelled above the floor 11 of the spiral A and in a manner so as to entirely avoid 90 the latter spiral. The cars entering the 95 building are therefore entirely independent of the cars leaving the building which travel along the spiral A which is likewise intermediate the portions of the spiral B. It is understood that the height of the garage is 100 unlimited and therefore, the spirals A and B may be continued to any length desired.

A car being on either of the spirals A and B can pass to the other spiral as the case may be by reason of the substantially horizontally connecting cross-over passageways D which connect the spirals at the points along the axis of the spirals where the entrance and exit spirals would cross each other if spirals were projected on a vertical plane. One of these cross passages D is preferably provided at each rise of each of the spirals A and B.

Referring to Figure 2 I have illustrated 110 a floor plan providing a plurality of stalls

or the like E preferably extending adjacent the outside of each of the spirals A and B and preferably throughout the entire length and height of these spirals. I may also 5 provide additional stalls E' on the substantially horizontal cross-over passages D. I may further provide additional parking stalls E² adjacent the stalls E', but on the spirals A and B. The various stalls are 10 preferably arranged to provide an aisle of suitable dimensions whereby the cars may travel around the spirals A and B and across from one spiral to the other at a plurality of heights in the building as shown 15 in Figure 2.

In the ordinary course of operation in parking cars in the garage, the cars will enter at the point C and continue to travel on the spiral B until the proper stall is 20 reached. If the stall assigned to any particular car is on the spiral B the car will continue its travel around the spiral B until such stall is reached when the car will be parked therein. Should the stall for any 25 car be on the spiral A the car in entering will travel around the spiral B until the approximate height of the stall is reached when the car will cross over on the corresponding passage D to the spiral A and 30 travel in the direction of the cars leaving the building on this spiral until such stall is reached, when the car will be parked therein. In leaving the garage any car which is parked on the spiral A will simply continue 35 to travel downwardly of this spiral until the point of exit F is reached. Should any car be parked on the spiral B the operator will cross over to the spiral A at the nearest passage D and then continue in the same manner 40 down the spiral A to the point of exit F as before.

It should be understood that various modifications of my invention may be made such as changing the arrangement of the 45 parking stalls and the like. If desired an elevator G may be provided and the space at the corners of the building as indicated at H may be used as wash rooms, storage rooms or for other purposes as desired, such as additional elevators.

It should be understood that the columns and other supports for the spirals A and B and the construction in general may be suitably arranged. Furthermore, it will be apparent 55 that instead of providing the entrance and exit passages C and F on different sides of the building these passages could be arranged on the same side of the building without departing from the spirit 60 of the invention. Furthermore, instead of one set of spirals A and B additional sets of concentric spirals could be provided if desired.

While it is preferable to incline the spiral 35 passageways A and B uniformly throughout

their length for convenience in building it should be understood that the spirals may have certain of their sides in horizontal planes connected by ramps or the like with the other portions of the spiral formed in any manner desired.

For example instead of warping the spirals A and B uniformly throughout their widths, the outer portions including the parking stalls E may be brought into inclined planes extending longitudinally of the respective sides of the building.

It will be noted that my invention provides a garage building construction comprising a pair of separate and distinct parallel planes in the manner of a double concentric spiral, the inner edges connecting to substantially level planes about which the latter planes are formed, the level planes serving to connect one spiral with the other.

If desired, my garage construction may be used with various systems of traffic operation. For example, instead of using spirals A and B separately for traffic leaving and entering the building respectively, the spirals might be used in common to vehicles entering and leaving. Thus the traffic entering the building might follow a path successively on spirals B and A by a continuous counterclockwise path around the group of stalls E² and E' shown to the left of the passage D in Figure 2. The traffic leaving the garage could then follow a clockwise path around the stalls E' and E² shown to the right of Figure 2. The passages D would thus be utilized at each level by the traffic entering and leaving the building. If desired, either or both of the groups of stalls E' and E² may be omitted. Further courses of traffic paths may be used as found convenient.

By the term "stall" as referred to in the specification and claims, I preferably mean any parking space indicating means such as floor markings, curbs, etc.

While it is believed that from the foregoing description, the nature and advantage of my invention will be readily understood, I desire to have it understood that I do not limit myself to what is herein shown and described and that such changes may be resorted to when desired as fall within the scope of the claims.

What I claim as my invention is:

1. A garage building having walls arranged rectangularly comprising a plurality of helical floors within the building, one floor constituting an entrance spiral and the other floor constituting an exit spiral, the convolutions of one spiral interposed between those of the other spiral, said spirals continuously sloping substantially throughout their lengths and being formed with driveways substantially throughout their lengths to respectively and separately ac-

commodate travelling of vehicles entering and leaving the garage, a plurality of substantially level cross passages providing cross driveways permitting travel of the vehicles in a substantially horizontal direction from one of said spirals to the other and vice versa at points along the common axis of the spirals where the spirals cross each other when projected on a vertical plane.

2. A garage building comprising a plurality of helical floors, the convolutions of one spiral interposed between those of the other spiral, said spirals continuously sloping substantially throughout their lengths, and a plurality of horizontal cross passages connecting the separate spirals. 10
15

In testimony whereof I affix my signature.
ALFRED G. WHEELER.
